UNITED STATES PATENT OFFICE.

JOHN J. WANKO, OF WESTPORT, MARYLAND.

GLASS-MOLDING APPARATUS.

994,806.

Specification of Letters Patent. Patented June 13, 1911.

Application filed February 4, 1910. Serial No. 542,130.

To all whom it may concern:

Be it known that I, JOHN J. WANKO, a citizen of the United States, residing at Westport, in the county of Baltimore and 5 State of Maryland, have invented new and useful Improvements in Glass-Molding Apparatus, of which the following is a specification.

This invention relates to apparatus for 10 molding bottles and other articles of glassware, and particularly to glass molding apparatus of that type in which a blank of the article is first formed in a blank mold and then transferred to a blow mold in 15 which the operation is completed by the blowing process.

In order to facilitate the flow of the 20 charge of molten glass from the gathering rod to the blank mold, it is customary to swab the mold after each operation with oil or other lubricant. If this is not done and the mold is left dry, the glass will not roll freely and properly into the mold and the 25 resultant article will be imperfect in form, the body wall of the article generally varying at different points in thickness. On the other hand, if too much oil is used, the glass is liable to be discolored thereby, or by the 30 smoke or particles of products of combustion from the burning of the oil in the hot mold. To avoid these objections it is necessary to oil the mold with care and to clean the same at intervals, but, as these operations 35 interfere with the output of the operator, they are as a general rule but imperfectly carried out, the operator preferring to run the risk of making a certain percentage of defective articles.

The object of the present invention is to 40 provide a means by which a blast or current of air may be directed into the blank mold, whereby the same will be freed from excess oil, smoke or other foreign substances, thus insuring the production of perfectly 45 formed articles free from defects on each operation.

The invention consists of the features of construction, combination and arrangement 50 of parts hereinafter fully described and claimed, reference being had to the accompanying drawings, in which:—

Figure 1 is a front elevation, partially in 55 section, showing adjacent blank molds and forming plungers of a molding apparatus of the character described and the means

for clearing the molds. Fig. 2 is an end elevation, showing in addition a modified means for supplying a blast of air to each mold. Figs. 3 and 4 are sectional views showing different forms of nozzles which 60 may be employed. Fig. 5 is a cross section on the line 5—5 of Fig. 3.

Referring to the drawings, the numeral 1 designates two adjacent spaced blank molds of a battery of molds commonly employed in an apparatus of this character, in which a molder or operator and a batch boy or assistant are in charge of a designated number of molds. In this type of apparatus, the molds are successively supplied 70 with glass and the blanks formed by the action of coöperating plungers, after which the blank is transferred from the blank mold to a blow mold, in which the operation is completed by the usual blowing action. 75

Arranged in suitable relation to the molds is the usual air supply pipe 2 from which lead branches 3 on lines between the molds, three of such branches being shown in the present instance, the central branch carrying a T-coupling 4 and the end branches or terminal branches L-couplings 5. As shown, each mold 1 has an upper forming cavity 6 and a flanged head 7 to receive a detachable cap 8 having an opening in communication with the cavity 6 for the passage of the forming stem 9 of the plunger 10, the body of the bottle or article being formed in the cavity 6, while the neck thereof is formed in the opening of the cap 8. After the formation of the pattern and retraction of the plunger, the pattern and cap are transferred to the blow mold, in which the operation is completed by blowing, as heretofore described. Each mold 95 has a bottom opening 11 communicating through a duct or passage 12 with the lower end of the channel 6, which duct is controlled by an upwardly opening check valve 13, adapted to permit air to enter the cavity 100 to prevent the formation of a vacuum in the withdrawal of the blank, and thereby permit the latter to be easily removed. It is customary in molding apparatus of this character, to provide the conductors 3 with 105 nozzles arranged to discharge a blast of air against the plunger to keep the same at a sufficiently low temperature. Preferably these same conductors or others leading from the air supply pipe 2 are employed for 110

supplying blasts of air to keep the molds 1 free from foreign substances liable to discolor the glass.

In the embodiment shown in Fig. 1, 5 curved or goose-necked nozzles 14 are fitted in the ends of the T-coupling 4, preferably by a screw-threaded connection, and each of said nozzles is formed with a pair of ducts or passages 15 and 16. The ducts or 10 passages 15 of the two nozzles are straight and extend clear through the horizontal arms of the nozzles to direct jets of air upon the plungers 10, as will be readily understood. The ducts 16, on the other hand, extend 15 through both arms of the nozzles and open through the lower ends of the latter for directing currents of air downward at an angle upon the upper surfaces of the molds 1 and into their cavities 6. Preferably each 20 nozzle is threaded at its lower end to receive a cap 17 having an outlet opening 18 therein for the discharge of the blast, but the use of this cap is not essential. Similar nozzles are connected with the elbows 5 of 25 the outer branches 3, the nozzle of each outer branch being arranged for coöperation of the adjacent nozzle of the central branch or the supply of blasts of air to the contiguous mold and plunger.

30 It will be understood from the foregoing description that upon the removal of the formed blank from each blank mold blasts of air will be directed into the cavity 6, whereby any excess amount of oil contained 35 therein or any smoke or other foreign impurities will be blown out, leaving the mold clear for the successive forming operation and consequently insuring the production of clear blanks free from inequalities of thickness or discoloration. As soon as the blank 40 is removed, the blast entering the forming cavity blows out any smoke or carbon which may be present, the operator then swabs the mold with the usual amount of oil, and upon 45 the removal of the swab the blast is again directed into the cavity with the result that any free oil contained therein will be discharged. Hence, the mold will be kept clean and free from the presence of substances 50 liable to prevent the easy and rapid feed of the glass into the mold or to discolor the same during the process of forming the glass by the action of the plunger, and as this operation will be secured without care or 55 attention on the part of the operator the advantage thereof will be apparent.

In Fig. 2 of the drawing, I have shown the addition to the structure described of a modified mode of supplying the air blast to 60 each blank mold, which modification consists in extending from the pipe 2 a branch or conductor 19 to a point beneath the mold and providing said branch with a discharge valve or nozzle 20 arranged to inject a jet of air 65 into the bottom chamber 20, so that when the

cavity 6 is open the valve 13 will be forced open under pressure allowing the blast to pass upward through the cavity 6 and clear the same of impurities. This mode of feeding the blast upward in the manner described may be employed in that type of apparatus in which the molds are mounted upon a rotating carrier or table with advantageous results.

70 Each nozzle 14 preferably has the horizontal portion of its passage 16 extending through the nozzle from end to end parallel with the passage 15, the outer end of said passage 16 being, however, closed by a plug 16'. This plug may be removed, in the event 75 that the passage should become clogged for the introduction of a suitable clearing tool.

80 In Fig. 3, I have shown a modified form of goose-neck nozzle in which the passages 15 and 16 extend through tapered nipples 15^a and 16^a, which construction may be employed in some instances.

85 In Fig. 4, I have shown a further modified form of nozzle fitted in each end of the branch 4, each of said nozzles comprising a 90 screw plug 14^a in which the passages 15^b and 16^b are formed. In this construction the outer end of the passage 16^b, which extends straight through the nozzle, is closed by a plug 16^c, and an angular outlet 16^d for 95 the discharge of the blast is provided.

95 Having described the invention, I claim:—

1. In a glass blowing apparatus, the combination with a blank mold, and a vertically movable forming plunger, of an air supply pipe arranged above the level of the mold, branches carried by said pipe and arranged on opposite sides of the plunger, and nozzles upon said branches provided with horizontal ducts for discharging currents of air against the plunger and obliquely arranged ducts for discharging blasts of air downwardly into the forming cavity of the mold.

100 2. In a glass blowing apparatus, the combination with a blank mold, and a vertically movable forming plunger, of an air supply pipe arranged above the level of the mold, and a discharge nozzle carried by said pipe, and provided with ducts for respectively discharging blasts of air at different angles therefrom and respectively against the surface of the plunger and downwardly into the forming cavity of the mold.

105 3. In a glass blowing apparatus, the combination with a blank mold, and a vertically movable forming plunger, of an air supply pipe arranged above the level of the mold, and an air blast nozzle upon said pipe provided with a horizontal duct for discharging a current of air against the plunger and a downwardly projecting obliquely arranged duct for discharging a blast of air downwardly into the forming cavity of the mold.

110 4. In a glass blowing apparatus, the com-

bination with a blank mold, and a vertically
movable forming plunger, of an air supply
pipe arranged above the level of the mold,
branches carried by said pipe on opposite
5 sides of the plane of movement of the plun-
ger, and nozzles carried by said branches
and each provided with ducts for respec-
tively discharging blasts of air inwardly
against the plunger and downwardly at an
10 angle into the forming cavity of the mold.

5. In a glass blowing apparatus, the com-
bination with a blank mold, and a vertically
movable forming plunger, of an air supply
pipe arranged above the level of the mold,
15 and a nozzle carried by said pipe and dis-
posed above the mold and at one side of the
plane of movement of the plunger, said
nozzle being provided with a duct for dis-
charging a blast of air laterally against the
20 plunger and a duct for discharging a blast
of air downwardly into the mold.

6. In a glass blowing apparatus, the com-
bination with a blank mold, and a vertically
movable forming plunger, of an air supply
pipe arranged above the level of the mold, 25
a coupling carried by said pipe, and a nozzle
detachably fitted within said coupling and
having a horizontal portion and an angu-
larly bent portion, said horizontal portion
being provided with a duct for discharging 30
a blast of air laterally against the forming
plunger and said angularly bent portion be-
ing provided with a duct for discharging a
blast of air downwardly at an angle into
the mold. 35

In testimony whereof I affix my signature
in presence of two witnesses.

JOHN J. WANKO.
